By Arthur H. Ewald,

Attorney.

UNITED STATES PATENT OFFICE

ISAAC M. PEASE, OF CINCINNATI, OHIO, ASSIGNOR TO THE OHIO TRUSS COMPANY, A CORPORATION OF OHIO

TRUSS PAD CONSTRUCTION

Application filed January 14, 1930. Serial No. 420,702.

The present invention relates to pads for trusses.

The principal object of the invention is to provide a pad having a connecting head, the parts being of such construction that the head may be readily replaced or changed without necessitating the renewal of the entire pad. The pad may thus be adapted to treat varying conditions at a minimum of expense for renewal or replacement.

Further objects of the invention will appear from the following detailed description thereof:

In the drawing:

Figure 1 is a plan view of a truss pad constructed in accordance with this invention.

Figure 2 is a longitudinal section of said pad.

Figure 3 is a transverse section of the pad.

Figure 4 is a longitudinal section of the pad having a modified form of head.

Figure 5 is a transverse section of the pad as illustrated in Figure 4.

The numeral 1 indicates a casing or cover,

the same being constructed of elastic material, as, for instance, rubber. The cover 1 is provided with a reticulated non-skid surface

2. The rear side of the cover is provided with a large opening 3 through which a re-

silient filler or pad 4 is inserted. The front

portion of the cover is provided with a smaller central opening 5 for the interchange-able head 6. The head 6 is provided

with a base 7 which has an annular groove

8 into which the edge of the cover around the opening 5 fits, thus securing the head in the cover. The contacting portion of the head

6 may be of any suitable construction.

In Figures 1, 2 and 3, the upper contacting

portion 9 of the head is supported by a long narrow and flexible connector 10. The portion 9 is thus adapted to flex suitably to fit the pad comfortably and efficiently to the part to be treated.

In Figures 4 and 5, a modified form of head is shown in which the upper portion 11 is centrally depressed, as shown at 12, such construction being particularly adapted to various conditions.

As will be understood, the particular form

of replaceable head is not of the essence of the present invention, which consists in the provision of an interchangeable head which may be readily inserted into or removed from a truss pad cover.

Having thus fully described my invention, what I claim as new and desire to secure by Letters Patent is:

A truss pad comprising a resilient filler, an elastic cover adapted to fit around said filler, said cover having an opening, an independently constructed head, said head being undercut to form a contacting portion, a base of area substantially coextensive with said contacting portion and adapted to rest flatly against said filler, and a resilient connector between said base and contacting portion, said base being provided with a peripheral groove adapted to receive the edge of said cover around said opening whereby said head is secured in said cover by the compression of said filler.

ISAAC M. PEASE.
